HANDLE LOCK FOR SUCTION CLEANERS

Edwin J. Balluff, Detroit, Mich., assignor to
Eureka Williams Corporation, a corporation of
Michigan

Application September 25, 1944, Serial No. 555,606

11 Claims. (Cl. 306—13)

1

This invention relates to suction cleaners and has particular reference to a handle lock therefor.

In suction cleaners of the floor type where the handle is pivoted adjacent the rear wheels of the cleaner, it is desirable to lock the handle in its vertical or parked position. This invention has for its principal object the provision of a novel and efficient handle lock and release therefor.

Principal objects of the invention are to provide:

A new and improved handle lock;

A handle lock which may be easily released by a natural movement of the hand of an operator when the handle of the cleaner is to be moved from its parked to an operating position.

Other objects and advantages of the invention will be apparent from a consideration of the following specification taken in conjunction with the accompanying drawings, of which there are two sheets and wherein:

Fig. 1 is a side elevational view of a cleaner embodying the invention;

Fig. 2 is an enlarged fragmentary side elevational view of the handle mounting and lock therefor with the handle in its vertical or parked position;

Fig. 3 is a view similar to Fig. 2 but with the handle in its lowermost or horizontal position;

Fig. 4 is a rear elevational view, partly in section, of the mechanism as illustrated in Fig. 2; and

Fig. 5 is a plan view of the mechanism as illustrated in Fig. 2.

A suction cleaner in connection with which my invention is particularly useful may comprise a casing having front and rear wheels 10 and 12; a nozzle 14 having a mouth 16 presented toward the surface covering upon which the cleaner is supported, a handle 18 and a bag 20. The cleaner casing further includes a motor driven suction creating means operatively connected to the mouth of the nozzle for creating a flow of air into the nozzle and thence through the machine into the bag 20 where the dirt entrained in such air is separated therefrom.

The front wheels 10 may be mounted on the cleaner casing in any suitable fashion rearwardly of the nozzle, while the rear wheels 12 may be mounted one on each end of the axle 22 which in turn is mounted on two spring leaves or members 24, such spring leaves or members 24 being constructed and arranged so as to position the rear wheels 12 relative to the casing as illustrated in Figs. 1 and 2 when the handle 18 is in its parked

2

position; that is, to bias the rear end of the cleaner upwardly away from the wheels 12. The spring leaves or members 24 thus resiliently mount the rear end 26 of the cleaner on the rear wheels 12 and in such a manner that the rear wheels 12 may move vertically relative to the rear 26 of the cleaner when the handle is in its parked position. However, with the handle 18 in its vertical position the rear wheels 12 will be positioned approximately as shown and preferably so that the mouth 16 of the nozzle 14 is slightly spaced above the surface covering to be cleaned.

The handle 18 is formed at its lower end with a socket 28 between the side walls 30 of which a pin 32 extends. The pin 32 is journaled in bearings provided on the side arms of a bracket 34, such bracket being provided with feet 36 which are suitably affixed to the rear end 26 of the cleaner. In this manner the handle 18 is pivoted on the cleaner and at a point generally above the rear axle 22 thereof. The handle in Figs. 1 and 2 is shown in its vertical or parked position and in Fig. 3 in its horizontal position and is pivoted to the cleaner by means of pin 32 and its bearings, for movement between these two positions. The operating position generally would be approximately midway between the two positions in which the handle is illustrated in Figs. 2 and 3, that is, approximately at a 45° angle relative to the horizontal.

A coil spring 38 surrounding pin 32 has one of its ends 40 hooked into a slot in one arm of the bracket 34, while the other end 42 of the coiled spring is hooked around a pin 44 projecting inwardly from the side 30 of the socket 28. The coiled spring 38 forms a counterbalance for the handle 18. The pin 44 cooperates with a top part of the bracket 34 at one side thereof in the manner illustrated in Fig. 3 to limit clockwise rotation of the handle 18 relative to the bracket, and cooperates with another part of the bracket 34 on the other side of the pin 32 as illustrated in Fig. 2 to limit counterclockwise rotation of the handle 18.

The socket 28 on one side is provided with a laterally extending pin 46 which forms a locking member or latch for operative engagement with a hook-shaped keeper or locking member 48. The keeper 48 is in the form of a hook and is formed on the upper end of a link 50 which passes through a slot in one of the feet 36 of the bracket and the rear end of the cleaner casting, and at its lower end 52 is provided with an aperture 55 through which the axle 22 extends.

The link 50 is free to pivot on the axle 22. With the parts arranged as illustrated in Fig. 2, the keeper 48 cooperates with the pin 46 under the influence of spring 24 to lock the handle against pivotal movement relative to the cleaner in order to permit the cleaner to be picked up by means of the handle 18 with the parts arranged as illustrated in Fig. 1.

By depressing the rear end of the cleaner, for example by pushing downwardly on the handle 18, the spring leaves or members 24 will yield sufficiently so as to permit the pin or latch 46 to move downwardly relative to the keeper 48 sufficient to clear the end 56 thereof, whereupon the handle may be pivoted backwardly to its operating position.

A stop 58 formed on the link 50 cooperates with a stop formed by the under surface of a locking plate 60 to limit the downward movement of the rear end of the cleaner 26 relative to the rear wheels 12 and axle 22. Another link 62 lying next to the link 50 and having its lower end pivoted on the axle 22 is provided with a latch 64 which is adapted to engage a stop formed by the upper surface of the locking plate 60 when the rear end 26 of the cleaner is depressed for locking the rear end 26 of the cleaner against vertical movement relative to the rear wheels 12 and the axle 22.

The link 62 is biased by a spring 66 into the position illustrated in Fig. 3 so that as soon as the latch 64 clears the upper surface of the locking plate 60 the spring 66 will move the link 62 to the position illustrated in Fig. 2, provided that the pin 46 moves due to the pivotal movement of the handle sufficiently to permit this action to take place.

The upper end of the link 62 is bifurcated to form a fork 68 which is adapted to accommodate the pin 46 after disengagement thereof from the keeper 48 and during the initial pivotal movement of the handle 18 in a clockwise direction from the position illustrated in Fig. 2. In fact, the arms of the fork 68 are so positioned relative to the pin 46 and the keeper 48 that the handle 18 cannot be moved to its operating position without engaging the latch 64 with the locking plate 60 as illustrated in Fig. 3. As the fork 68 is open at the top, further pivotal movement of the handle is provided for, and when the handle is restored to its parked position the pin 46 will enter the fork 68 and shift the same so as to disengage the latch 64 from the locking plate 60. When the handle is in its operating position the mouth 16 of the nozzle will be properly positioned relative to the surface covering on which the cleaner is supported.

The subject matter disclosed and claimed herein is more broadly claimed in the prior co-pending application of George R. Coss, Serial No. 522,182, filed February 10, 1944, for "Suction cleaner."

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. In a suction cleaner, a body having a bracket, a handle pivoted on said bracket, a wheel, means including a spring forming a movable mounting for said wheel on said body which pro-

vides for relative movement between said wheel and body and which is arranged to bias said body to the limit of its movement away from said wheel when the cleaner is supported on the floor by said wheel, a locking element on said handle, a locking member connected with said mounting so as to be movable therewith relative to said body, said locking member being engageable with said handle locking element for locking said handle against pivoting movement on said bracket, said body having a stop with which said locking member is engageable to limit movement of said body toward said wheel, a second locking member connected with said mounting and movable therewith relative to said body, said second locking member being engageable with a part on said body for locking said body against movement away from said mounting when said stop is engaged with said first-mentioned locking member, said second locking member being arranged relative to said first-mentioned locking member so as to be disengaged from said part when said first-mentioned locking member is engaged with said handle locking element.

2. In a suction cleaner, a body, a handle pivoted on said body, a wheel, means including a spring forming a movable mounting for said wheel on said body which provides for relative movement between said wheel and body and which is arranged to bias said body to the limit of its movement away from said wheel when the cleaner is supported on the floor by said wheel, a locking element on said handle, a locking member connected with said mounting so as to be movable therewith relative to said body, said locking member being engageable with said handle locking element for locking said handle against pivoting movement on said bracket, said locking member being disengageable from said locking element upon depressing said body against the force of said spring, said body having a stop with which said locking member is engageable to limit movement of said body toward said wheel, a second locking member connected with said mounting and movable therewith relative to said body, said second locking member being arranged relative to said body, said second locking member being engageable with a part on said body for locking said body against movement away from said mounting when said stop is engaged with said first-mentioned locking member, said second locking member being arranged relative to said first-mentioned locking member so as to be engaged with said part when said first-mentioned locking member is disengaged from said handle locking element.

3. In a suction cleaner, a body, a handle pivoted on said body, a wheel, means including a spring forming a movable mounting for said wheel on said body which provides for relative movement between said wheel and body and which is arranged to bias said body to the limit of its movement away from said wheel when the cleaner is supported on the floor by said wheel, a locking pin on said handle, a hook-shaped locking member connected with said mounting so as to be movable therewith relative to said bracket, said locking member in one position thereof being hooked over said pin for locking said handle against pivoting movement on said bracket, said hook-shaped locking member being disengageable from said pin upon depressing said body by downward pressure on said handle sufficient to overcome the force of said spring, said body having a stop with which said locking member is engageable to limit movement of said body to-

5

ward said wheel, a second locking member connected with said mounting and movable therewith relative to said body, said second locking member being engageable with a part on said body for locking said body against movement away from said mounting when said stop is engaged with said first-mentioned locking member, said second locking member being arranged relative to said first-mentioned locking member so as to be disengaged from said part when said first-mentioned locking member is engaged with said handle locking pin.

4. In a suction cleaner, a body, a handle pivoted on said body, a wheel, means including a spring forming a movable mounting for said wheel on said body which provides for relative movement between said wheel and body and which is arranged to bias said body to the limit of its movement away from said wheel when the cleaner is supported on the floor by said wheel, a locking element on said handle, a locking member connected with said mounting so as to be movable therewith relative to said body, said locking member being engageable with said handle locking element for locking said handle against pivoting movement on said body, said body having a stop with which said locking member is engageable to limit movement of said body toward said wheel, a second locking member connected with said mounting and movable therewith relative to said body, said second locking member being engageable with a part on said body for locking said body against movement away from said mounting, when said stop is engaged with said first-mentioned locking member, said second locking member being arranged relative to said first-mentioned locking member so as to be engaged with said part when said first-mentioned locking member is disengaged from said handle locking element, and means for preventing any substantial pivotal movement of said handle until said second locking member is engaged with said part.

5. In a suction cleaner, a body, a handle pivoted on said body, a locking member comprising a laterally extending pin on said handle, a hook-shaped locking member mounted for movement relative to said locking pin, said hook-shaped locking member in one position thereof relative to said pin being hooked over said pin for locking said handle against pivoting movement on said body and in another position thereof being disengaged from said pin so as to permit pivoting movement of said handle.

6. In a suction cleaner, a body having a bracket, a handle pivoted on said bracket, supporting wheels, means including a spring forming a mounting for one of said wheels on said body which provides for relative movement between said wheel and body and which is arranged to bias said body upwardly to the limit of its movement away from said wheel when the cleaner is supported on the floor by said wheels, a locking pin on said handle, a hook-shaped locking member connected with said mounting so as to be movable therewith relative to said bracket, said locking member in one position thereof being hooked over said pin for locking said handle against pivoting movement on said bracket, said hook-shaped locking member being disengageable from said pin upon depressing said body relative to said one of said wheels so as to permit pivoting movement of said handle.

7. In a suction cleaner, a body having a bracket and a guide slot, a handle pivoted on said

6

5 bracket, supporting wheels, means including a spring forming a mounting for one of said wheels on said body which provides for relative movement between said wheel and body and which is arranged to bias said body upwardly away from said wheel, a locking pin on said handle, a hook-shaped locking member connected with said mounting and so as to be movable therewith relative to said bracket, said locking member extending through said guide slot and in one position thereof being hooked over said pin for locking said handle against pivoting movement on said bracket, said hook-shaped locking member being disengageable from said pin upon depressing said body by downward pressure on said handle sufficient to overcome the force of said spring.

8. In a suction cleaner, a body having a bracket and a guide slot, a handle pivoted on said bracket, supporting wheels, means including a spring forming a mounting for one of said wheels on said body which provides for relative movement between said wheel and body and which is arranged to bias said body upwardly away from said wheel, a handle lock comprising a locking pin on said handle, and a hook-shaped locking member connected with said mounting and so as to be movable therewith relative to said pin, said locking member extending upwardly from said mounting through said slot and in one position thereof being hooked over said pin for locking said handle against pivoting movement on said bracket, said hook-shaped locking member being disengageable from said pin upon depressing said body by downward pressure on said handle sufficient to overcome the force of said spring, a second locking member connected with said mounting so as to be movable therewith relative to said pin and engageable with a part of said body upon disengagement of said hook-shaped locking member from said pin for locking said handle lock in its disengaged condition.

9. In a suction cleaner having a wheeled body arranged for movement on a floor, an upstanding handle pivotally mounted on said body for swinging movement from a substantially vertical position downwardly and rearwardly through an arc to an operating position and back to said vertical position, releasable locking mechanism associated with the mounting of said handle on said body and automatically operable for positively locking said handle in its vertical position relative to said body upon swinging movement of said handle into said vertical position while said body is supported on said floor so as to permit said cleaner to be picked up by means of said handle while maintaining the relative positions of said body and handle, said locking mechanism comprising a laterally extending pin on said handle and a hook-shaped locking member mounted for movement relative to said locking pin, said hook-shaped locking member in one position thereof relative to said pin being hooked over said pin for locking said handle against pivoting movement on said body and in another position thereof being disengaged from said pin so as to permit pivoting movement of said handle, said locking mechanism being constructed and arranged to be released by bodily depressing said handle from its normal vertical position while said body is so supported on said floor, so as to permit swinging movement of said handle to an operating position for propelling said cleaner.

10. In a suction cleaner arranged for movement on a floor, a spring mounted body having an upstanding handle pivoted thereto for propelling

the cleaner, releasable locking mechanism associated with said handle and body and operable for automatically positively locking said handle in a vertical position relative to said body upon movement of said handle to such position while said body is so supported on the floor so as to permit said cleaner to be picked up by means of said handle while maintaining the relative positions of said body and handle, said locking mechanism including a releasable connection constructed and arranged to be released by depressing the rear end of said body while said body is supported on said floor, so as to permit pivotal movement of said handle to a position for propelling said cleaner, said locking mechanism comprising a pin on said handle and a hook-shaped locking member mounted for movement relative to said pin.

11. In a suction cleaner having wheels yieldably supporting said cleaner on a floor, an upstanding handle pivoted on said cleaner for propelling the same, locking mechanism associated with said cleaner and handle and operable for automatically positively locking said handle in a vertical position relative to said cleaner upon movement of said handle to such position while

5
